SOUND RECORDING APPARATUS

Glenn L. Dimmick, Haddonfield, N. J., assignor
to Radio Corporation of America, a corpora-
tion of Delaware

Application March 31, 1939, Serial No. 265,279

5 Claims. (Cl. 179—100.3)

This invention relates to sound recording apparatus and more particularly to apparatus for recording sound on film by what is known as the penumbra type of variable density system.

The subject matter of this application is an improvement on the apparatus described and claimed in my Patent No. 2,095,317, issued October 12, 1937. In the said patent, apparatus is described and claimed for making a variable density sound record by the penumbra method and the present apparatus distinguishes thereover in that the apparatus is so modified that either volume compression or variation in the slope of the variable density curve, or both, may be produced.

In the performance of my invention, I take advantage of the fact that the intensity gradient of the penumbra depends upon the distance of the penumbra mask from the filament or filament image. When the mask is located close to the filament the intensity varies gradually, whereas as the mask approaches the area on which the penumbra is to be projected the gradient becomes quite steep. By moving the penumbra mask back and forth in accordance with the sound volume, I am able to vary the intensity gradient as desired and to thereby change the variation in light intensity for given galvanometer deflection, as desired, and I take advantage of this fact to produce volume compression or change in slope of the variable density curve as may be required.

One object of the invention is to provide an improved method of and apparatus for variable density recording.

Another object of the invention is to provide an improved apparatus for volume compression.

Another object of the invention is to provide an improved type of variable density sound track.

Another object of the invention is to provide a penumbra type of recording apparatus with a movable penumbra mask.

Another object of the invention is to provide an improved type of squeeze track recording.

Another object of the invention is to provide an improved penumbra mask.

Other and incidental objects of the invention will be apparent to those skilled in the art from a reading of the following specification and an inspection of the accompanying drawings, in which

Figure 1 is a diagrammatic illustration of a penumbra recorder with the penumbra mask in one position;

Figure 2 is an illustration corresponding to

Fig. 1 but showing the penumbra mask in a different position;

Figure 3 is a diagram illustrating the effect on light intensity of the shift in penumbra mask position;

Figure 4 illustrates a modified form of apparatus using two penumbra masks;

Figure 5 is a curve of galvanometer deflection plotted against slit illumination for the apparatus shown in Fig. 4;

Figure 6 is a diagrammatic illustration of an apparatus for shifting the penumbra mask along the axis of the optical system in accordance with the volume of the sound recorded to produce volume compression;

Figure 7 is a diagrammatic illustration of an apparatus for shifting the penumbra mask along the optical axis of the recording optical system and simultaneously perpendicular to the said axis in order to produce both volume compression and ground noise reduction;

Figure 8 illustrates a modified form of apparatus for accomplishing either volume compression, ground noise reduction, or both, as desired;

Figure 9 is a curve showing slit illumination plotted against galvanometer deflection for the apparatus shown in Fig. 8;

Figure 10a is a view of a penumbra mask of the customary type from one end of the optical system;

Figure 10b is a view, corresponding to 10a, of an improved form of penumbra mask;

Figure 11 is a curve showing galvanometer deflection plotted against slit illumination for the form of penumbra mask shown in Fig. 10b; and

Figure 12 shows an apparatus similar to that of Fig. 6 combined with a double vane shutter in order to produce a squeeze track recording combined with volume compression.

Referring first to Fig. 1, this figure shows the portion of a recording optical system from the lamp toward the galvanometer in an apparatus such as shown in my patent above referred to. The lamp filament is indicated at 10 and, as shown, is of appreciable diameter since an electrical filament is used. The opaque penumbra vane is shown at 11 reaching to the optical axis of the system. The penumbra is indicated as lying in the plane 12, which plane is usually the plane of the recording slit in an optical system. The height of the penumbra is indicated by the bracket and ranges from a maximum of intensity at the top to substantially zero intensity at the bottom.

In Fig. 2 the penumbra mask or vane 11 is

shown as moved farther to the right than in Fig. 1 and it will be apparent that in this case the penumbra covers the smaller distance indicated by the bracket in this figure. It will be also 5 apparent that the light intensity at the top of the penumbra in Fig. 2 is the same as at the top of the penumbra in Fig. 1, while at the bottom the light intensity likewise falls to zero. In other words, the range of light intensity in the short 10 penumbra in Fig. 2 is the same as in the longer penumbra shown in Fig. 1 but this range covers a shorter distance.

If the light from the arrangement shown in Figs. 1 and 2 is directed to a galvanometer mirror 15 and from the galvanometer mirror through a slit to the film, as illustrated in the aforesaid patent, or in Fig. 12 of the present application, then the variation in light intensity for a given galvanometer deflection is as indicated in Fig. 3. 20 If the normal galvanometer position in relation to the slit be considered as fifty per cent illumination, then the penumbra shown in Fig. 1 will have the slope indicated in the solid line when galvanometer deflection is plotted against slit 25 illumination and it will be apparent that this slope is rather gradual. On the other hand if the penumbra mask or vane is moved to the position shown in Fig. 2, the relatively shorter penumbra will provide the much steeper slope shown in the dashed line and a correspondingly greater change in illumination will be produced in proportion to the galvanometer deflection.

One way to take advantage of this effect is shown in Fig. 4. In this case a pair of penumbra masks 13 and 14 are provided which are spaced along the optical axis. It will be apparent that light from the filament 10 passing the mask 13 will produce the upper half of the penumbra in the image plane 12 which will be spread out 40 in the same manner as is the penumbra in Fig. 1. On the other hand the light from the upper portion of the filament passing the second mask 14 will produce the lower half of the penumbra in the image plane 12 which will be correspondingly 45 shorter or compressed, as is the case in Fig. 2. If the light beam after passing these penumbra masks is deflected by a galvanometer mirror in the customary manner, then the galvanometer deflection as plotted against slit illumination will 50 appear as shown in Fig. 5, where the lower portion of the curve indicates the relatively steep slope of the lower portion of the penumbra in Fig. 4, while the upper portion of the curve indicates the more gradual slope of the upper portion 55 of the penumbra shown in Fig. 4. It will be apparent that the use of these two fixed penumbra masks accordingly produces a type of volume compression in accordance with the curve of Fig. 5.

60 In the form of the invention shown in Fig. 6 the penumbra vane 11 is connected to a movable member of the motor 15 which in turn is connected to an appropriate rectifier, filter and timing circuit 16. This rectifier, filter and timing circuit arrangement may be a conventional ground noise reduction amplifier, such as shown and described, for example, in McDowell Patent 1,856,197, or in Kreuzer Patent 1,999,700. When the envelope of the sound waves changes, the motor 15 which may, as illustrated, consist merely of a solenoid with a movable iron plunger, is actuated to shift the penumbra mask 11 along the optical axis of the system. The effect of movement of this vane depends on the direction of 70 connection of the apparatus. If increased sound 75

volume causes the vane to move toward the left to increase the height of the penumbra, then compression of the volume range is obtained. If the apparatus is so connected that increased sound volume causes the vane 11 to move to the right and to thereby decrease the height of the penumbra in the plane 12 to the smaller dimension indicated by the lines 17, then volume expansion results, the penumbra position when the vane 11 is in the left hand position being indicated by the lines 18.

In the apparatus shown in Fig. 7, the penumbra mask 11 is arranged to rotate about the pivot 19 while the motor 15 is connected as shown in Fig. 6 to swing the penumbra mask about that pivot. A second fixed penumbra vane 20 is provided as described and claimed in the joint application of J. L. Underhill and myself, Serial No. 210,592, filed May 28, 1938, RCV Docket 6032. In this arrangement movement of the penumbra vane 11 about the pivot 19 in accordance with the envelope of the sound waves accomplishes both ground noise reduction as described and claimed in the said application due to the vertical component of motion, or motion perpendicular to the optical axis, and the movement of the vane along the optical axis accomplishes volume compression simultaneously. If the rotary motion indicated in Fig. 7 is not desired, then the motor illustrated in Fig. 6 may be bodily substituted for that shown in Fig. 7 and set at an angle with the optical axis so that the vane 11 will move along a fixed axis intersecting the optical axis and producing the same effect as shown in Fig. 7. The fixed vane 20 is so placed that it 35 forms an optical end stop for the penumbra. The vane 11 is so adjusted that it may move past the end of the vane 20 but any such further movement does not affect the penumbra. This arrangement permits the use of an amplifier in which the current operating the motor 15 varies in direct instead of inverse proportion to the envelope of the sound waves.

In the above described forms of the invention, the penumbra has been produced by a vane of opaque material. The same result may be accomplished as shown in Fig. 8 by a plate of opaque material having a convex curve upon its surface as the portion of the surface to which the rays are tangent is the only part affecting the penumbra. The rays of light from different portions of the filament strike the plate at different portions along the optical axis and by appropriately choosing the surface curvature of the plate the light intensity distribution of the penumbra may be varied as desired. For example, the plate shown in Fig. 8 will produce a curve of galvanometer deflection plotted against slit illumination substantially as shown in Fig. 9 and this curve may be varied as desired by varying the curvature. By moving the plate in Fig. 8 up and down in accordance with the sound envelope both volume compression and noise reduction may be secured. The relation between the quantities of volume compression and noise reduction may be controlled by choosing or shifting the location of the pivot 21 about which the curve plate 22 is rotated. In order to avoid stray light effects and similar undesirable reflecting effects, the upper surface of the movable plate 22 should be appropriately rendered non-reflecting. For example, the surface may be sandblasted and finished in black or it may be provided with transverse grooves to provide a substantially continuous series of diaphragm edges 75

or narrow diaphragms may be secured thereto closely adjacent to each of them.

The active edge of the penumbra vanes and masks above described and heretofore used has been straight when they lay at right angles to the optic axis and when they were viewed along the optic axis, as, for example, from the position of the light filament, this arrangement being shown in Fig. 10a. The edge of the penumbra mask, however, may be provided with "saw teeth" of triangular or other shape, as shown in Fig. 10b. This saw tooth arrangement will produce a penumbra having an intensity distribution substantially as shown in Fig. 11. In this figure the dashed lines indicate the intensity distribution, in terms of galvanometer deflection, plotted against slit illumination for a penumbra mask having a straight edge, while the solid line indicates the corresponding functions of a penumbra mask having a saw tooth edge, such as shown in Fig. 10b. It will be apparent that a more or less S-shape curve results. This shape of curve is sometimes desired in order to make overloading of the sound track less noticeable and correspondingly less objectionable. This effect may be produced likewise in the penumbra mask of Fig. 8 by providing longitudinal V-shaped grooves on the plate 22.

Instead of the saw tooth edge shown in Fig. 10b I may provide the penumbra mask of 10a with a translucent edge or with an edge of graded translucence in order to accomplish the same result as is accomplished by the saw tooth edge. Alternatively, I may make the entire penumbra mask partly transparent or translucent to give a diffused illumination and the edge of this mask may, in turn, have a graded light translucence.

For a constant amplitude of galvanometer vibration and a constant brightness of light source, the volume of sound obtained from a penumbra type variable density record is inversely proportional to the height of the penumbra and directly proportional to the length of the recording light beam which determines the width of the sound track. If a shutter controlling the length of the light beam and therefore the width of the sound track is mechanically or electrically coupled to the penumbra vane in such a manner that the

height of the penumbra is directly proportional to the length of the recording beam, then the sound volume obtained from the track would be proportional to the original volume but the surface noise due to dirt, scratches and film grain would decrease with decreasing sound volume. Such an automatic squeeze track recording system is illustrated in Fig. 12 which shows the portion of a recording optical system from the lamp to the galvanometer mirror. In this arrangement a double vane shutter may be used, such, for example, as described and claimed in Hasbrouck Patent 2,102,778 or Baker Patent 2,102,776. In this arrangement the penumbra vane is connected to the shutter actuating motor so that the shutter vanes and penumbra vane are simultaneously actuated. It will be apparent that the shutter motor and the penumbra motor may be independent, as, for example, by using a penumbra vane motor, such as illustrated in Fig. 6 or Fig. 7, connected to the output of the same amplifier as a shutter motor such as shown in the patents just referred to.

Having now described my invention, I claim:

1. In a recording optical system of the penumbra type, a penumbra mask consisting of a plate of opaque material convexly curved toward the optical axis of the optical system.
2. In a recording optical system of the penumbra type, a penumbra mask consisting of a plate of opaque material convexly curved toward the optical axis of the optical system, and means for moving the said mask toward and away from the optical axis in accordance with the envelope of the sound waves to be recorded.
3. A penumbra mask for use in a sound recording optical system, consisting of a body of opaque material having serrations therein along the edge defining the penumbra.
4. A penumbra mask for use in a sound recording optical system, consisting of a body of opaque material having a partially light transmitting portion along the edge defining the penumbra.
5. A penumbra mask for use in a sound recording optical system, consisting of a body of opaque material having a portion of graded light transmission along the edge defining the penumbra.

GLENN L. DIMMICK.
